(57) **CLAIM**

The ornamental design for a golf swing training kit, as shown and described.

DESCRIPTION

FIG. 1 is a front top perspective view of a golf swing training kit showing my new design;

FIG. 2 is a top view thereof;

FIG. 3 is a front view thereof;

FIG. 4 is a rear view thereof;

FIG. 5 is a bottom view thereof;

FIG. 6 is a side view thereof;

FIG. 7 is a side view thereof opposite that of FIG. 6;

FIG. 8 is a front top perspective view of a plane part of the golf swing training kit showing the new design with the base portion removed;

FIG. 9 is a top view thereof;

FIG. 10 is a front view thereof;

FIG. 11 is a rear view thereof;

FIG. 12 is a bottom view thereof;

FIG. 13 is a side view thereof;

FIG. 14 is a side view thereof opposite that of FIG. 13;

FIG. 15 is a front top perspective view of a base part of the golf swing training kit showing the new design with the plane portion removed;

FIG. 16 is a rear perspective view thereof;

FIG. 17 is a top view thereof;

FIG. 18 is a front view thereof;

FIG. 19 is a bottom view thereof;

FIG. 20 is a rear view thereof;

(Continued)

FIG. 21 is a side view thereof; and,
FIG. 22 is a side view thereof opposite that of FIG. 21.
